UNITED STATES PATENT OFFICE.

CLEMENT S. MOSSOP, OF SEAVILLE, NEW JERSEY.

RAILROAD-CROSSING.

No. 890,291.

Specification of Letters Patent.

Patented June 9, 1908.

Application filed January 11, 1907. Serial No. 351,751.

To all whom it may concern:

Be it known that I, CLEMENT S. Mossop, a citizen of the United States, residing at Seaville, Cape May county, State of New Jersey, have invented a new and useful Railroad-Crossing, of which the following is a specification.

In railway crossings constructed under practiced methods the jar and vibration which occurs when the trucks of a car are passing thereover is not only very detrimental to the life of the component parts of the car and the rails but the noise caused by such jar and vibration is objectionable.

One of the main objects of my present invention is to devise a novel construction of a crossing in which the jar, vibration and noise will be overcome and to the above ends my invention consists, in its broad scope, of a movable member adapted to be actuated by the wheels of the car, whereby a substantially continuous track in any desired direction may be obtained so that such noise, jar and vibration will be practically eliminated.

My invention further consists of a novel construction of a rotatable member having a one way track thereon which is suitably mounted at the intersection of the rails, and novel means coacting with said member and the wheels of the car, whereby a continuous track in the desired direction may be obtained.

My invention further consists of a novel means of returning the rotatable member to normal position after a movement, whereby one of the tracks may always be continuous. By this feature the device is not subject to constant rotation but remains stationary except when the cross track is to be used. After a car has passed along the cross track and over the main track the rotatable member is automatically returned to alignment with the main track.

It further consists of other novel features of construction, all as will be hereinafter fully set forth.

For the purpose of illustrating my invention, I have shown in the accompanying drawings one embodiment thereof which will give satisfactory and reliable results in practice, although it will be understood that the various instrumentalities of which my invention consists can be variously arranged and organized and that my invention is not

limited to the precise arrangement and organization of these instrumentalities, as herein shown.

Figure 1 represents a plan view of a railway crossing embodying my invention. Fig. 2 represents a section on line $x-x$ Fig. 1. Fig. 3 represents a sectional elevation of my invention. Fig. 4 represents a section on line $y-y$ Fig. 2. Fig. 5 represents a section on line $z-z$ Fig. 4. Fig. 6 represents a side elevation of a portion of the actuating mechanism. Figs. 7 and 8 represent side elevations similar to Fig. 6 but showing the positions the parts assume at different stages of the operation. Fig. 9 represents a plan view of Fig. 8.

Similar numerals of reference indicate corresponding parts in the figures.

Referring to the drawings, 1 designates the rails of one track which are crossed at an angle by the rails 2 of another section of track, said rails being provided with a tread 3 and a gutter 4 of any desired construction.

5 designates supports located at the intersection of each track and to which the rails 1 and 2 are suitably secured.

6 designates a lower bearing block secured in or integral with the support or casing 5.

7 designates a rack guide seated on the block 4 above which is located a block or bushing 8 which rests thereon and serves as a further support for the rails.

9 designates a ring or bushing which is provided with the gutters 10 registering with the gutters 4 of the rails 1 and 2, the upper face of the bushing 9 contiguous the gutters 10 being in the same plane as the tread of the rails so that the member 9 forms a continuation of the rails 1 and 2.

11 designates a rotatable member having the bearings 12, 13, 14 and 15 which coact respectively with the bearings 11', 12' and 13' in the block 8 and 14' in the block 6, it being noted that the bearings 13, 15, 13' and 14' are shown as being preferably conical in form. The rotatable member 11 is provided with a one way track 1' having a tread 3' and a gutter 4' which are adapted to register with the tracks formed in the member 9 which latter may be integral, if desired, with the block 8.

16 designates a gear or pinion mounted on the member 11 and adapted to coact with racks 17 and 18 mounted in the rack guide 7,

it being noted that in the present instance two sets of these racks are employed.

As most clearly seen in Figs. 6 to 9 inclusive, the lever arm 17 has pivoted at its inner end at 19 a lever or link 20, the opposite end of which is pivoted at 21 to a block or bracket 22, which is fixedly mounted on a shaft 23 in any suitable manner, said shaft 23 in the present instance being suitably journaled in the rack guide 7. The rack arm 18 has pivoted thereto at 24 a lever or link 25, the opposite end of which is pivoted at 26 to a block or bracket 22, it being noted that the pivotal point 26 is in the present instance diametrically opposite the pivot 21. The rack guides 7 in the present instance are closed at the ends, as at 27, in order to form a positive stop for the outward movement of the rack arms 17 and 18.

28 designates a pulley fixedly mounted on the shaft 23.

29 and 30 designate conductors which pass around the pulley 28 in opposite directions and are secured to said pulley by means of any suitable fastening device such as a pin 31.

32 designates an aperture extending through the block 6 and the casing 5 through which the conductors 29 or 30 are adapted to pass.

33 designates a block or bracket which is eccentrically pivoted as at 34 to the web of the rail or the rail support 35, as is clearly indicated in Fig. 3, and to this block or bracket 33 is secured in any suitable manner the conductor 30.

36 designates a link pivoted at 37 to the block 33, the opposite end of said link being pivoted at 38 to one end of a lever arm 39, it being noted that the block 33, in the present instance, is cut away or recessed as at 40, in order that one end of the lever arm 39 may pass therewith during the operation. The lever 39 is fulcrumed at 41 to a suitable fixed point in the present instance to one of the brackets or guides 42 carried by the member 35. The guides 42 serve to maintain in proper position a plunger or movable member 43 having at its upper end a preferably reduced portion 44, which is adapted to pass through the aperture 45 in the gutter 4. The lower end of the member 43 is provided with a cam face 46, which coacts with the lever 39 to actuate the same. The lever 39 will preferably be constructed of suitable resilient material, in order that there will be a slight yielding action if any part of the apparatus should become in any manner clogged or obstructed, thus preventing any breaking or disarrangement of the coacting parts. The conductor 29 is secured to a construction similar to that just described, said conductor being fastened to a block 47 pivoted at 48 and having secured thereto one end of a link 49, the opposite end of which is pivoted to a

lever 50 fulcrumed at 51 to a suitable fixed part such as the guides 52 for the plunger or movable member 53 provided with a cam face 54 coacting with the lever 50. The member 53 is provided with a preferably reduced end or stem 55, which passes through an aperture 56 in the gutter 4. The actuating mechanisms to which the ends of the conductors 29 and 30 are respectively secured are located at any suitable distance from the crossing, in order that the movable members may be automatically actuated by the co-action of the wheels of the car with the plunger members 44 or 55 before the forward wheels of said car reach the intersecting tracks.

The operation may now be readily understood. Assuming that a car is traveling toward the left of Fig. 1 on the tracks 1, the parts being in their normal position as indicated in Fig. 1, as soon as the forward wheels of the car contact with the rod or plunger 44, the weight of the car will cause said plunger to be depressed thereby causing the cam face 46 to coact with the lever 39, and since said lever is pivoted to the end of the block or bracket 33, to which the conductor 30 is secured, said block 33 will be moved outwardly on its fulcrum, thereby causing the conductor 30 to be drawn toward the right and since this conductor is secured to the pulley 28, which is fixedly mounted on the shaft 23, the shaft 23 will be partially rotated and the rack arms 17 and 18 will move from their normal position, as indicated in Fig. 6, and the links 20 and 25 and their adjuncts will assume the position seen in Figs. 8 and 9. The rack arms 17 and 18 move away from the shafts 23 and engage with the gears or pinions 16 carried by the rotatable members 11 and 105 cause said members to be partially rotated so that the one-way track 13 therein will register with the tracks 3 and a substantially continuous rail will be formed, it being understood that the shaft 23 is connected at its opposite end with similar rotatable members, rack arms and actuating mechanism therefor, so that the rotatable members employed will be simultaneously actuated, so that the tread and gutter on each member 11 will register with the tread and gutter of the bushing 9, or the tracks 1 when said bushing 9 is dispensed with, although in practice I prefer to employ such a bushing or equivalent member. After the front wheels of the car have 120 passed the crossing and coact with the operative portion 55 of the plunger 53, said plunger will be depressed, and the block 47 to which the conductor 29 is secured, will be moved outwardly and the pulley 28 will be 125 rotated in a reverse direction to that just described, which will cause the rack arms 17 and 18 to be drawn toward the shaft 23 and as these rack arms coact with the gears 16, the rotatable members 11 will be returned to 130

their normal position, as indicated in Fig. 1, thus forming a continuous track on the rails 2.

In the present instance, for convenience of illustration, I have shown the operative 5 plungers 44 and 55 and their adjuncts as being located on the same side of the track but it will be apparent that one of these may be arranged on the opposite track if so desired and the mechanism employed as well 10 as the operation thereof will be similar to that already described with the exception that an additional pulley will be placed on the shaft 23.

Owing to the novel manner in which the 15 rotatable members are mounted there is no liability of dirt or foreign matter coming in contact with the bearings or with the actuating mechanism.

It is to be understood that the crossing and 20 the different mechanisms pertaining thereto are in practice covered by any suitable type of casing or covering such as is well known in the art. In the present instance I have preferred to show one form of actuating 25 mechanism for the rotatable members which gives satisfactory and reliable results in practice but it is to be understood that my invention in its broad scope comprises movable members located at the intersection of 30 the tracks and adapted to be automatically actuated to form continuous rails in either direction.

It will now be apparent from the foregoing 35 that I have devised a novel and useful construction of crossing which embodies the features of advantage enumerated as desirable in the statement of invention and the above description and while I have in the present instance shown and described one embodiment 40 thereof which gives satisfactory and reliable results in practice, it is to be understood that my invention is susceptible of modification in various particulars without departing from the spirit and scope of the 45 invention or sacrificing any of its advantages.

Having thus described my invention, what I claim as new and desire to secure by Letters Patent, is:—

50 1. In a crossing, intersecting tracks, movable members mounted at the intersection

thereof, and means on the same track for rotating said members in opposite directions.

2. In a crossing, intersecting tracks, movable members mounted at the intersections 55 thereof, means coacting with the wheels of a car before it reaches the crossing to rotate said members in one direction, and means coacting with the wheels of the car after it passes the crossing for returning said members to their normal position. 60

3. In a crossing, intersecting tracks, track members rotatably mounted at such intersections and normally registering with the tracks in one direction, means coacting with 65 a car for causing said members to register with a track in a different direction, and means coacting with the same car for causing said members to return to their normal position.

4. In a crossing, intersecting tracks, track 70 members rotatably mounted at such intersections and normally registering with the tracks in one direction, gears carried by said members, rack arms coacting with said gears, links pivoted to said arms, a cross piece pivoted to said links, a shaft on which said cross piece is fixedly mounted, and means on 75 opposite sides of the crossing coacting with the wheels of the car to rotate said shaft in opposite directions. 80

5. In a crossing, intersecting tracks, track members rotatably mounted at such intersections and normally registering with the tracks in one direction, gears carried by said members, rack arms coacting with said 85 gears, a shaft to which said rack arms are operatively connected, a pulley mounted on said shaft, conductors secured to said pulley and passing therearound in reverse directions, means on one side of the crossing 90 coacting with one of said conductors and the wheels of the car to cause said members to register with the tracks in a different direction, and means on the opposite side of the crossing coacting with the wheels of the car 95 and the other of said conductors for causing said members to return to their normal position.
